Q. SANTICOLA

CLOTHES WASHING APPARATUS

Filed June 27, 1927

INVENTOR.
Quentin Santicola
BY *James R. Snyder*
ATTORNEY

UNITED STATES PATENT OFFICE.

QUENTIN SANTICOLA, OF PITTSBURGH, PENNSYLVANIA, ASSIGNOR OF ONE-FIFTH TO
FRANK CHIRCOSTA, OF PITTSBURGH, PENNSYLVANIA.

CLOTHES-WASHING APPARATUS.

Application filed June 27, 1927. Serial No. 201,600.

My invention relates to a clothes washing apparatus, and the primary object of the invention is to provide a washing apparatus of the character described, which is power driven, to thoroughly clean excessively soiled garments by a rubbing action.

Further objects of the invention are to provide a device of the class stated which is simple in its construction and arrangement, strong, durable and efficient in its use, automatically adjustable, compact, and comparatively inexpensive to manufacture.

With the foregoing and other objects in view which will appear as the description 15 proceeds, the invention resides in the combination and arrangement of parts and in the details of construction hereinafter described and claimed, it being understood that changes in the precise embodiment of the 20 invention can be made within the scope of what is claimed without departing from the spirit of the invention.

In the drawing wherein like numerals of reference designate corresponding parts 25 throughout the several views:—

Figure 1 is a side elevational view, partly in section, of a washing apparatus constructed in accordance with the invention.

Figure 2 is a top plan view thereof.

30 Figure 3 is a sectional view on line III—III, Fig. 1.

Referring in detail to the drawing 1 denotes a rectangularly shaped metallic casing which is open at its top. A supporting 35 bar 2 is connected, in a suitable bearing 3, adjacent to each end of the casing side walls 4 and adjacent to the top edge of the latter. Each of the supporting bars 2 is connected to its associated bearing 3, at the approximate 40 center of its length and is disposed on the inner side of respective casing side walls 4.

The supporting bars 2 are mounted for 45 oscillatory movement in the casing 1 and carry a horizontally disposed lower rubbing plate 5 and a correspondingly disposed upper rubbing plate 6, the latter being arranged directly over the lower rubbing plate 5. The lower rubbing plate 5 is provided with a transversely corrugated top 7 and the upper rubbing plate 6 is formed

with a similar transversely corrugated bottom 8.

The forward end of each side of the lower rubbing plate 5 is provided with a fixed, 55 and substantially L-shaped depending bearing bracket 9, which is pivotally connected, at its lower end, as at 10, to the lower end portion of respective supporting bars 2.

The forward end of each side of the upper rubbing plate 6 is provided with a fixed, 60 apertured bearing lug 11. The latter is pivotally connected to an inwardly disposed pivoting pin 12 which is fixed in a slide block 13, mounted for vertical movement 65 on the top portion of respective supporting bars 2. This arrangement permits of the convenient removal of the upper rubbing plate 6 when required.

The connection of the lower and upper 70 rubbing plates 5 and 6, with the supporting bars 2, in the manner herein stated, is such that the oscillatory movement of the latter will impart a reciprocatory movement to the lower and upper rubbing plates 5 and 6. 75 As the lower and upper rubbing plates 5 and 6 are respectively attached below and above the pivotal connecting bearings 3, of the supporting bars 2, the reciprocating movement of the rubbing plates 5 and 6 will 80 always be in opposite directions relatively to each other.

The lower ends of the supporting bars 2, disposed adjacent to the forward end of the casing 1, are connected by a transversely extending cross-rod 14, and the lower ends 85 of the supporting bars 2, disposed adjacent to the rear end of the casing 1 are likewise joined by a transversely extending cross-rod 15. A connecting rod 16 is pivotally 90 connected, at its respective ends, to the cross- rods 14 and 15 preferably centrally of the length of the latter.

The cross-rod 14 is pivotally connected, as 95 at 17, to the rear end of an actuating rod 18. The latter is eccentrically and pivotally connected to the worm gear 19. The worm gear 19 is driven by a worm 20, loosely mounted on the shaft 21 of the driving motor 22. A clutch 23 is mounted on the motor shaft 21 and is operable to engage or disengage the worm 20, to permit of the control 100

of the washing apparatus without suspending the operation of the motor 22, in the usual manner.

The upper rubbing plate 6 is formed with an enlarged opening 23, which is provided with a door 24. The latter is hingedly connected, as at 25, and is provided with a latch 26 and handle 27. The door 24 constitutes a rubbing portion of the upper rubbing plate 6 and is provided for facilitating the positioning of the clothes between the lower and upper rubbing plates 5 and 6, previous to the rubbing operation.

An elevating handle 28 extends along each side wall 4 of the casing 1 and is carried at the lower end of a pair of elevating levers 29 which are pivotally connected centrally of their lengths, as at 30, to the brackets 31, fixed to respective ends of the casing side walls 4. The upper ends of the elevating levers 29 abut against the under side of respective horizontally disposed plates 32, one of which is fixed to and projects outwardly from each of the sliding blocks 13. The manual depression of the elevating handles 28 will slide the blocks 13 upwardly, thereby elevating the upper rubbing plate 6, which is connected to the latter. When the elevating levers 29 are in the elevating position, their engagement with the plates 32 will cause them to maintain the upper rubbing plate 6 in the elevated position. The manual release of the elevating levers 29 will cause the upper rubbing plate 6 to return from its elevated position by gravity.

Each corner of the upper rubbing plate top carries a fixed, vertically disposed pin 33, for engaging removably mounted, apertured weight disks 34. The latter are provided to supply the necessary weight to the upper rubbing plate 6 to properly effect the rubbing operation.

The motor 22 is suitably housed above the level of the casing bottom to prevent possibility of the former contacting with the drippings resultant from the rubbing operation. The casing 1 is provided with a drain cock 35 to drain all drippings which normally accumulate in the casing 1.

The clothes to be cleaned are spread on the corrugated top of the lower rubbing plate 5. This is accomplished by depressing the elevating handles 28 to elevate the upper rubbing plate 6 and by opening the door 24. The clothes to be rubbed are, of course, first thoroughly soaked and soaped to facilitate the cleaning thereof. After the clothes have been spread upon the top of the lower rubbing plate 5, the upper rubbing plate 6 is released to rest directly on the top of the clothes. To the weight of the upper rubbing plate 6 itself is added an additional number of weight disks 34 to establish the proper pressure to best effect the cleansing

of the clothes by the rubbing operation. The motor 22 is now started, or if already running, the clutch 23 is shifted to engage the worm 20. The operation of the latter will cause the reciprocation of the rubbing plates 5 and 6, in opposite directions, relatively to each other, thoroughly cleansing the clothes from soil that can only be removed from the latter by a rubbing action.

What I claim is:

1. A washing apparatus of the character described comprising a pair of horizontally disposed rubbing plates, a support for said pair of rubbing plates, and means for imparting a reciprocatory movement to said pair of rubbing plates, one of said pair of rubbing plates being vertically shiftable on said support.

2. A washing apparatus of the character described comprising a pair of horizontally disposed rubbing plates, a support for said pair of rubbing plates, means for imparting a reciprocatory movement to said pair of rubbing plates, one of said pair of rubbing plates being vertically shiftable on said support, one of said pair of rubbing plates arranged directly above the other of said pair of rubbing plates and provided with an enlarged opening, and a door for closing said opening.

3. A washing apparatus of the character described comprising a pair of horizontally disposed rubbing plates, a support for said pair of rubbing plates, means for imparting a reciprocatory movement to said pair of rubbing plates, one of said pair of rubbing plates being vertically shiftable on said support, the opposed faces of said pair of rubbing plates being formed with transversely extending corrugations.

4. A washing apparatus of the character described comprising a pair of horizontally disposed rubbing plates, a support for said pair of rubbing plates, means for imparting a reciprocatory movement to said pair of rubbing plates, one of said pair of rubbing plates being vertically shiftable on said support, one of said pair of rubbing plates arranged directly above the other of said pair of rubbing plates and provided with an enlarged opening, a door for closing said opening, the opposed faces of said pair of rubbing plates being formed with transversely extending corrugations.

5. In combination, a washing apparatus of the character described comprising a pair of horizontally disposed rubbing plates, a support for said pair of rubbing plates, one of said pair of rubbing plates arranged directly above the other of said pair of rubbing plates, means for imparting a reciprocating movement to said pair of rubbing plates in opposite directions relatively to each other, the upper of said pair of rubbing plates being vertically shiftable on

said support, said upper rubbing plate further formed with an enlarged opening, means for elevating said upper rubbing plate on said support, and for maintaining said upper rubbing plate in the elevated position, the opposed faces of said pair of rubbing plates being formed with trans-

versely extending corrugations, and weight elements removably supported on the said upper rubbing plate. 10

In testimony whereof I affix my signature.

QUENTIN SANTICOLA.
